[57] CLAIM

The ornamental design for a support for phonograph records during cleaning or the like, as shown and described.

DESCRIPTION

FIG. 1 is a top plan view of a support for phonograph records during cleaning or the like, showing my new design;

FIG. 2 is a side elevational view thereof;

FIG. 3 is a sectional view taken along line 3—3 of FIG. 1;

FIG. 4 is a bottom plan view thereof;

FIG. 5 is a top plan view of a second embodiment of a support for phonograph records during cleaning or the like;

FIG. 6 is a sectional view taken along line 6—6 of FIG. 5; and

FIG. 7 is a bottom plan view thereof.

FIG. 1

FIG. 5

FIG. 6
